RAGGLE BLOCK

Richard E. Campfield, Richmond, Ind.

Application November 9, 1939, Serial No. 303,523

7 Claims. (Cl. 108—26)

This invention relates to improvements in raggle blocks. More particularly the invention relates to improvements in raggle blocks used to cover or protect the free ends of flashings or roofing materials which are used on roofs. It is an object of the invention to provide an improved raggle block of simple construction.

It has been found to be advantageous to cover or protect the free ends of flashings or roofing material from rain or from water collecting on roofs. Protection of the free ends of the flashing prevents water leaking between the flashing and the wall, and serves to make the roof water tight. Different methods of protecting the ends of the flashing have been tried with varying degrees of success. By one method the flashing is sealed against the wall with plastic materials such as tar, pitch, or asphalt. This type of material is waterproof, but it is difficult to apply it evenly enough to make the seal between the flashing and the wall water tight. As a result, openings occur between the wall and the flashing, and water can leak through them. Such leaks make this type of protection ineffective and, therefore, undesirable. Another method of protection uses raggle blocks which extend over the ends of the flashing and protect them from the rain and weather. This type of block is usually designed to receive the ends of the flashing and to permit the ends to be sealed in by a suitable plastic material such as tar, pitch, or asphalt. The protection afforded the flashing by the use of raggle blocks is increased by setting the blocks a short distance above the surface of the roof. This prevents water which may collect at the edges of the roof from entering the block, leaking through or around the plastic material, and over the ends of the flashing. Placing the raggle blocks above the level of the roof makes the roof water tight, but has heretofore necessitated the bending of the roofing material. The bending of the roofing material weakens it considerably and often causes it to crack after only short periods of use. Raggle blocks so designed are objectionable and inefficient since they materially shorten the life of the roofing material.

It is an object of this invention to provide a raggle block which will receive the ends of flashings or roofing material without necessitating the bending of the roofing material. Many raggle blocks now in use require the employment of a plastic material to seal in the ends of the flashings. These plastics are not only dirty and bothersome, but increase the cost of roofing work. By proper design, a raggle block can be made which

does not require the use of plastics such as tar, pitch, or asphaltum to make the roofing job water tight. Such a block obviates the expensive and bothersome use of plastics and is a more desirable block. It is an object of the present invention to provide a raggle block which will protect the ends of the flashing without requiring the use of plastics.

Where possible, the design of the raggle blocks should be made as simple as practical because such a design would reduce the installation cost as well as the cost of the block. By proper design, a raggle block may be made which will adequately and completely protect flashings inserted in the block without requiring the use of wedges or plastics to keep the ends of the flashings dry. It is an object of the present invention to provide a raggle block which will require only the insertion in it of the ends of the flashing, in order to protect them and keep them dry.

Other objects and advantages of the invention will appear in the specification, drawings, and accompanying claims.

The invention is shown and described in a preferred form in the drawings and accompanying description, but it is to be understood that the drawings and description do not limit the invention, and that it will be defined by the appended claims.

In the drawings—

Fig. 1 is a cross section of the wall and roof of a building showing the use of a raggle block in conjunction with flashing and roofing material.

Fig. 2 is a cross section of a wall and roof construction showing a raggle block used with a tile roof or floor.

Fig. 3 is a side view of a portion of a raggle block which uses wedges to hold the flashing in place.

Fig. 4 is a view of a raggle block using a single wedge to hold the roofing material.

Fig. 5 is a side view of a raggle block of optional design which has a locking device to lock the flashing in position against the wall, and

Fig. 6 is a view of a portion of a raggle block of optional design which obviates the use of plastics or wedges to waterproof the roofing material.

Referring to the drawings in detail, in Fig. 1 a wall of a building or structure is denoted by the numeral 10. Set in the wall 10 is a raggle block 12 which may be made in any convenient size or form. A preferred type is one which is the same size as one or more whole building blocks. This permits the block to be inserted in the wall easily

and quickly as the bricks are laid. An inclined portion 14 on the upper side of the front face of raggle block 12 acts to turn the rain. The front portion of the block 12 extends down to form an opening 16 to receive the flashing or roofing material 18. On the under side of the front portion of the block 12, a groove 20 may be formed to prevent water on the front of the block 12 from getting into the opening 16, since the water will drip off as it reaches the groove 20. The flashing or roofing material 18 may be inserted in the opening 16 and held there by a plastic material 22. Any suitable plastic material such as tar, pitch, or asphalt may be used. The plastic material is used to fill the opening 16 and to prevent water from getting over and down behind the flashing and roofing material 18. Because of the design of the front of the block, it can be seen that a plastic is not necessary since the low hanging portion 23 of the front of the block prevents any water from splashing onto the ends of the flashing. Where especially heavy rainfall is experienced, however, it might be advisable to more positively seal the flashing in the block by filling the opening 16 with any suitable plastic. The rear edge of the opening 16 in the raggle block 12 may be set flush with the front of the wall 10. This will permit the flashing 18 to be held flat against the wall 10 without bending it. The absence of a bend in the roofing material or flashing 18 insures a much longer life for the flashing and less likelihood of failure in the roofing job. The bottom of the front portion 23 of the block 12 in the preferred form of the invention is in the same plane as the bottom of the block 12. This will allow the block to be piled with other blocks without fear of breakage, as would be the case if the front portion projected below the plane of the bottom of the block 12.

In Fig. 2 a raggle block 24 is shown which is particularly applicable to floored or tiled roofs used on roof gardens. The top of the face of this block is set flush with the wall 10 and the lower portion of the front of the block 12 is arranged to form an opening 16. The front portion or face of the block overhangs the roofing tile 26 and acts as a watershed. The flashing 18 may be inserted in the opening 16 and held there by the tile 26. A plastic may be used to seal the space between the tile and lower end of the front of the block 12 if desired but this is not necessary since the tile and the block fit close enough to keep out the water. Even if the tile does not obstruct the opening 16, the low face on the block will keep water from spraying onto the top of the flashing. The groove 20 in the front portion 28 of the block 24 causes any water collecting on the lower side of the block 24 to drip off and keeps water out of the opening 16.

In Fig. 3 a portion of an optional form of block 30 is shown which makes use of two wedges to hold the flashing 18 in place against the wall. The front of the raggle block 30 may have an inclined portion 32 at the top which acts to turn the rain, and a lower portion 34 which forms an opening 16 in the block into which the flashing 18 may be inserted. The walls of the opening 16 are preferably made rough so that the wedges 36 and 38 will hold the flashing 18 in place without slipping. The wedges are made to fit together in such way that no water can get into the opening 16, and over and behind the ends of the flashing 18. The groove at the bottom of section 34 acts to keep water on the front of the block from

getting into the opening 16 and causes it to drip off.

Fig. 4 shows a portion of another optional form of block 40. This block may have an inclined face 42 which acts to turn water and also to form an opening 44. Into this opening the flashing 18 is inserted and held by a wedge 46. The use of a wedge avoids the use of plastics such as tar, pitch, or asphalt. These substances are dirty and sticky and are not easily applied, while a wedge can be driven in the opening 44 with little difficulty. The use of the wedge makes the flashing job cleaner and simpler. The walls of the opening 44 are made rough so the wedge and the flashing will not slip. The rear edge of the opening 44 is set flush with the wall 10 so the flashing does not have to be bent. Since the flashing 18 is straight, its life will be longer and the efficiency of the roofing job will be greater.

Fig. 5 shows another form of flashing block 48 in which an inclined portion 50 of the front of the block 48 acts to turn water and to protect the ends of the flashing. The front of the block 48 extends downward to form an opening 52. The flashing 18 may be inserted in the opening 52 as shown by dotted lines or it may be cut off below the opening 52. When the flashing extends into the opening, the form of the block 48 is such that even without the use of plastics or other means to close the opening 52, water cannot get behind the flashing. The block is set high enough above the roof level that the water on the roof will not rise far enough to reach it, while the lower portion of the face of the block extends down to prevent spray from the roof from reaching the ends of the flashing. The groove 20 in the lower portion of the front of the block 48, as before, keeps the water on the front of the block from getting into the opening 52. Where the ends of the flashing do not extend into the opening 52, the flashing piece 54 prevents water from reaching the ends of the flashing 18. A roller 56 and the flashing piece 54 are inserted in the opening 52 as shown in solid lines in the drawings. The roller is permitted to rest against the inclined face 48 of the opening and the front of flashing piece 54. The weight of the flashing piece will pull the roller 56 down into the position shown in the dotted lines and wedge the flashing piece 54 in position. The top of the flashing piece 54 and the roller 56 fit together and act to keep water out of the opening 52. The roller 56 and the flashing piece 54 keep the ends of the flashing 18 dry and, therefore, keep the roof water tight.

Fig. 6 shows a block which does not require the use of a plastic such as tar, pitch, or asphalt to hold the ends of the flashing. This is done by a spring 62 which bears against the projection 64 of the block 60 and holds the flashing 18 against the wall 68. This arrangement avoids the use of plastics which are dirty and difficult to apply. The design of the block holds the flashing against the wall and the front portion of the block prevents spray from the roof from touching the top of the flashing. This provides a simple method of waterproofing the flashing or roofing material.

The use of raggle blocks made in accordance with this invention does not necessitate the bending of the flashing or roofing material. Such bending not only weakens the roofing material but is inconvenient where the line of flashing blocks is horizontal and the roof slants. The cutting and bending of the roofing paper is bothersome and is avoided by the blocks made in accordance with the invention. The roofer need only

cut the paper approximately to length and insert it in the block where the ends of the flashing are protected by a plastic material, a suitable wedge, or by the front of the block. The use of raggle blocks which do not require the flashing or roofing material to be bent insures a long life for the roofing job.

The use of a raggle block which has an overhanging front portion has a number of advantages which the raggle blocks now in use do not have. One of these advantages is that the block may be used with metal flashing without any bending of the flashing. This minimizes the installation difficulties which are now met in roofing jobs making use of metal flashing. Whereas it is necessary to bend the metal flashing when it is used with the blocks now in use, it need only be fitted into the blocks made in accordance with the invention. Not only is it difficult to bend metal flashings, but the bending of the flashing will injure the galvanizing or other protective coating on the metal and shorten the life of the flashing.

Another advantage which this block possesses over the blocks now in use is that the receptacle for the flashing is built in the form of an overhanging portion. The use of an overhanging portion permits the main portion of the block to be made as strong as any building block since there is no opening in the main portion. This permits the raggle block to be used in any wall and not reduce the structural strength of the wall.

The use of a block which has an overhanging portion makes a roofing job of very attractive appearance. It avoids the visible openings now used on raggle blocks and the dirty appearance of the plastics used in the block. In the raggle blocks made in accordance with the invention, the opening is in the under side of the block and not visible. Because of this a smooth, uninterrupted front of pleasing appearance may be made for raggle blocks. This is a very important factor in roof gardens where the surroundings must be pleasing to the eye. The use of raggle blocks made in accordance with the invention permits a water tight roofing job which is very clean and pleasing to the eye.

It can be seen that raggle blocks made in accordance with the invention possess numerous advantages over and above the advantages possessed by the blocks now in use.

Whereas I have described a preferred form of my invention, it is obvious to persons skilled in the art that various changes and alterations can be made in the structure and form of the invention without altering its scope.

What I claim is:

1. A raggle block, adapted to form part of a wall, having a main portion of substantially rectangular shape and having a smaller portion adapted to extend beyond the wall and serve as a water shed, the under part of the smaller portion having a recess therein adapted to permit the fitting of roofing material therein without bending such roof material regardless of the position of the raggle block with respect to the roof.

2. A raggle block, adapted to form part of a wall, having a main portion of substantially rectangular shape and having a smaller portion adapted to extend beyond the wall and serve as a water shed, the under part of the smaller portion having a recess therein adapted to permit the fitting of roofing material therein without bending such roofing material regardless of the position of the raggle block with respect to the roof, the outer wall of said recess having an inclined face adapted to hold securely any caulking material placed in the recess. 5

3. A raggle block, adapted to form part of a wall, having a main portion of substantially rectangular shape and having a smaller portion adapted to extend beyond the wall and serve as a water shed, the under part of the smaller portion having an apronlike member which forms a recess in the smaller portion to receive the ends of roofing material, said apronlike member 10 having means to cause moisture on the apron to drip off. 15

4. A raggle block, adapted to form part of a wall, having a main portion of substantially rectangular shape and having a smaller portion adapted to extend beyond the wall and serve as a water shed, the under part of the smaller portion having a recess therein adapted to permit the fitting of roofing material therein without bending regardless of the position of the raggle 20 block with respect to the roof, and to receive a substantially waterproof adhesive such as pitch, the walls of said recess being corrugated to securely hold the roofing material and pitch in the recess. 25

5. A raggle block, adapted to form part of a wall, having a main portion of substantially rectangular shape and having a smaller portion adapted to extend beyond the wall and serve as a water shed, the under part of the smaller portion having a recess therein adapted to permit the fitting of roofing material therein without bending regardless of the position of the raggle block with respect to the roof, and to receive a substantially waterproof adhesive such as pitch, the 30 walls of said recess being roughened to securely hold the roofing material and pitch in the recess. 35

6. A raggle block, adapted to form part of a wall, having a main portion of substantially rectangular shape and having a smaller portion adapted to extend beyond the wall and serve as a water shed, the under part of the smaller portion having a recess therein adapted to permit the fitting of relatively inflexible roofing material therein. 40

7. A raggle block, adapted to form part of a wall, having a main portion of substantially rectangular shape and having a smaller portion adapted to extend beyond the wall and serve as a water shed, the under part of the smaller portion having a vertical recess therein adapted to permit the fitting of roofing material therein without bending such roofing material. 45
